UNITED STATES PATENT OFFICE.

GEORGE YOERGER, OF BROOKLYN, NEW YORK.

EXERCISING APPARATUS.

SPECIFICATION forming part of Letters Patent No. 757,709, dated April 19, 1904.

Application filed February 3, 1904. Serial No. 191,776. (No model.)

To all whom it may concern:

Be it known that I, GEORGE YOERGER, a citizen of the United States, residing at Brooklyn, in the county of Kings and State of New York, have invented certain new and useful Improvements in Exercising Apparatus, of which the following is a specification, such as will enable those skilled in the art to which it appertains to make and use the same.

10 The object of this invention is to provide an improved exercising apparatus of the punching-bag class which may be secured to an upright wall or any suitable upright support in a hall, room, or other compartment and by 15 means of which the vibration and noise occasioned by the use of apparatus of this class may be avoided; and with these and other objects in view the invention consists in an apparatus of the class specified constructed as 20 hereinafter described and claimed.

The invention is fully disclosed in the following specification, of which the accompanying drawings form a part, in which the separate parts of my improvement are designated 25 by suitable reference characters in each of the views, and in which—

Figure 1 is a sectional side elevation of my improved apparatus in position for use, and Fig. 2 a side view of one part thereof and 30 showing a modification.

In the practice of my invention I provide a bracket-arm a , provided at one end with a securing-plate a^2 , having a collar a^3 , into which the bracket-arm a is screwed, and by means 35 of the plate a^2 the bracket-arm may be secured to a wall or other upright support b , as shown in Fig. 1. The outer end of the bracket-arm a is provided with a depending tubular member a^4 , which is connected therewith by an elbow-coupling a^5 in the usual manner, or said 40 connection may be made in any preferred way, or the bracket-arm a and the depending tubular member a^4 may be formed integrally, if desired.

Connected with the lower end of the depending tubular member a^4 is a cup-shaped buffer c , and in the form of construction shown the buffer c is connected with the tubular member a^4 by means of a screw-threaded collar d , which 45 is screwed onto said member and provided

with a bottom flange or rim d^2 , to which the cup-shaped buffer c is bolted or otherwise secured, as shown at e , and in the form of construction shown the buffer c is provided with a central opening at c^2 , which corresponds 55 with the central bore of the tubular member a^4 , and that part of the buffer which adjoins said tubular member is beveled or rounded, as shown at c^3 .

Suspended centrally beneath the buffer c is 60 an ordinary punching-bag f , and the suspension of said bag in the form of construction shown is made by means of cord or similar flexible device f^2 , which passes up through the opening in the buffer c and partially 65 through the tubular member a^4 of the bracket-arm a and the end of which is passed out through an opening f^3 in the side of said tubular member and tied into a knot f^4 . As thus suspended it will be seen that the punching-bag 70 f is free to swing in all directions, and when struck by the fist in the usual manner the bag will fly up, as shown in dotted lines in Fig. 1, and will strike the concave surface of the cup-shaped buffer c and will swing back into the 75 position shown in full lines, and by reason of this method of supporting the bag there is no noise produced by the operation of the apparatus.

It is a well-known fact that in the operation 80 of apparatus of this class as usually constructed and supported there is a constant vibration, jolt, or jar, which is transmitted to a greater or less extent through the building in which the apparatus is placed; but by means 85 of my improvement this objectionable feature is obviated, the jolt, jar, or vibration being reduced to a minimum, if not entirely prevented.

In Fig. 2 of the drawings I have shown a 90 slight modification, in which instead of the cup-shaped buffer c I substitute a similarly-shaped buffer g , which consists of wire bent into the form of a spiral and one end of which is connected with the depending tubular member a^4 and the other with the collar d ; but this buffer may be made in still other forms and of other material without departing from the spirit of my invention or sacrificing its advantages.

My invention is not limited to the use of the horizontal arm *a* for supporting the buffer *c*, and any other suitable form of bracket may be employed having a depending portion with 5 which the buffer *c* may be connected.

Having fully described my invention, what I claim as new, and desire to secure by Letters Patent, is—

An exercising apparatus of the class described, comprising a bracket-arm adapted at 10 one end to be secured to a wall or other support and provided at its opposite end with a depending tubular member, a cup - shaped buffer secured to the lower end of said depending tubular member, and a punching-bag 15

suspended beneath said buffer by means of a flexible connection which passes upwardly therethrough and into said tubular member, the opening in the bottom of said buffer being beveled or rounded, substantially as shown 20 and described.

In testimony that I claim the foregoing as my invention I have signed my name, in presence of the subscribing witnesses, this 30th day of January, 1903.

GEORGE YOERGER.
